ELECTRIC CUT-OUT OR SWITCH.

1,018,501.

Specification of Letters Patent. Patented Feb. 27, 1912.

Application filed February 15, 1910. Serial No. 543,910.

To all whom it may concern:

Be it known that I, GEORGE A. JORDAN, a citizen of the United States, residing in the borough of Brooklyn, county of Kings, city and State of New York, have invented a certain new and useful Electric Cut-Out or Switch, of which the following is a specification.

The object I have in view is the production of an electric cut-out or switch, which will be protected from fire, moisture or gas, and which—if a short circuit occurs within it—will prevent the escape of flame, fire or sparks.

15 The particular object of my invention is to reduce the size of the switch, to simplify its construction, and to render it sure and certain of operation.

These objects I attain by means of mechanism illustrated in the drawings, in which:

20 Figure 1 is a plan view of the switch and box with the cover removed; Fig. 2 is a section thereof through the switch, box and cover; Fig. 3 is a perspective view of the 25 end of the key for operating the switch; Fig. 4 is a plan view and section of the pivoted member on the switch, with which the key is connected; and Fig. 5 is a detail view of the key guard.

30 In all of the views like parts are designated by the same reference characters.

In the drawings, 1 represents the switch proper which is supported upon a base 2 of insulating material and comprises the 35 fuse sockets 3, 3 and a pivoted switch 4. The pivoted switch 4 is of the knife-blade type and comprises two blades 5, 5 connected together by a cross arm of insulation 6. Any form of switch may be used, that 40 shown being chosen for the purpose of illustration only.

The switch 1 is secured within a box 7. This box is preferably made of cast iron and of rectangular shape and is provided 45 with a flange 8. A cover 9 is attached to the box and to the flange by means of bolts, as shown, packing being interposed between the cover and flange. The box has conduits 10, 10 for the entrance and exit of the leads 50 through the switch. The whole box is intended to be water, gas and fire tight. In the cover is an opening 11, through which a device is adapted to be inserted for the purpose of moving the switch to change it

from the open or closed position, or vice 55 versa. This device comprises a key and socket. The key 12 is in the form of a rod having a handle 13 at one end and a reduced extremity 14 with a cross head 15 at the other. The shape of this key is best shown 60 in Fig. 3. The reduced extremity 14 connects with the cross head 15. The length of the cross head is preferably no greater than the diameter of the larger portion of the key. The socket 16, shown in detail 65 in Fig. 4, is provided with ears 17, 17. These ears 17, 17 are secured by a pivot 18 to a clip 19, said clip being secured, as shown in Fig. 2, to the cross arm 6. The socket 16 has a keyhole opening 20 in its 70 outer face, said keyhole opening (as shown in Fig. 4) having a slot and an undercut portion 21. The size and shape of the slot and undercut portion are such that the cross 75 head of the key can be introduced and, when turned partly around, the inner arms of the cross head will engage with the undercut portion. The length of the key is such that the person operating the switch can introduce the key through the opening 11 80 and engage the cross head with the socket, give it a partial turn and thereby lock the key to the socket, and by a rectilinear movement can open or close the switch.

For the purpose of preventing the key 85 from coming in contact with any portion of the switch except the socket, a guard 22 is provided. This guard is in the form of an open ended semi-cylinder and is hinged to the inside of the cover 9 at 23. The free end 90 of the guard is connected to the cross arm 6 by means of a bail 24.

When the key is inserted into the opening 11 (assuming the switch to be closed) its end will be guided by the guard 22, so that 95 it will find its proper place in the socket 16, and, as the switch is opened, the bail 24 will move the guard to the position shown in dotted lines in Fig. 2. When the key is not in use, the opening 11 is adapted to be closed 100 by a screw cap 25, which may be secured to the collar by a chain, as shown. In order to keep the key from becoming lost, it may be secured to the cover by a chain 26, as shown.

For the purpose of keeping the socket 16 105 at a proper angle for the reception of the key, I prefer to proportion the ears 17, 17 as shown in Fig. 2, so that one corner of the

ear will engage with the clip 19, thus keeping the clip from turning farther upon its pivot 18.

In accordance with the provisions of the 5 patent statutes, I have described the principle of my invention, together with the apparatus which I now consider to represent the best embodiment thereof; but I desire to have it understood that the apparatus shown 10 is merely illustrative and that the invention can be carried out in other ways.

Having now described my invention, what I claim as new and desire to secure by Letters Patent, is:

- 15 1. The combination with a switch and a box therefor, said switch having an insulated socket said box having an opening in a wall, of a key introducible through the opening to engage with the socket and control the switch and means permitting relative movement of the switch and key.
- 20 2. The combination with a switch and a box therefor, said switch having a pivoted socket with a key hole slot therein, and said

box having an opening in a wall, of a key, 25 said key having a cross head on one extremity, said key being introducible through the opening into engagement with the socket to control the switch.

3. The combination with a box and a pivoted switch therein, said box having an opening in a wall, of a guard within the box between the switch and the opening, and a key introducible through the opening to control the switch. 30

4. The combination with a box and a pivoted switch therein, said box having an opening in a wall, a guard pivoted to the wall adjacent to the opening, and connected to the switch by a bail, and a key introducible through the opening into contact with the switch. 40

This specification signed and witnessed this fifth day of February, 1910.

GEORGE A. JORDAN.
